US00D903414S

(12) **United States Design Patent** (10) **Patent No.:** **US D903,414 S**
Guerin et al. (45) **Date of Patent:** **** Dec. 1, 2020**

(54) **COOKING BASKET**

- (71) Applicant: **SharkNinja Operating LLC**, Needham, MA (US)
- (72) Inventors: **Thomas Guerin**, Boston, MA (US); **Chris Martin**, Concord, MA (US); **Nathaniel R. Lavins**, Somerville, MA (US); **Da Deng**, Newton, MA (US)
- (73) Assignee: **SHARKNINJA OPERATING LLC**, Needham, MA (US)
- (**) Term: **15 Years**
- (21) Appl. No.: **29/679,922**
- (22) Filed: **Feb. 11, 2019**

(57) **CLAIM**

The ornamental design for a cooking basket, as shown and described.

DESCRIPTION

FIG. 1 is a perspective view of a cooking basket, showing our new design;

FIG. 2 is a front view of the embodiment shown in FIG. 1; FIG. 3 is a rear view of the embodiment shown in FIG. 1; FIG. 4 is a side view of the embodiment shown in FIG. 1; FIG. 5 is another side view of the embodiment shown in FIG. 1;

FIG. 6 is a top view of the embodiment shown in FIG. 1; and, FIG. 7 is a bottom view of the embodiment shown in FIG. 1.

The broken lines in the figures are for environmental purposes only and form no part of the claimed design.

The broken lines in the figures are for environmental purposes only and form no part of the claimed design.

1 Claim, 7 Drawing Sheets
